UNITED STATES PATENT OFFICE

104,358

DESIGN FOR A VANITY CASE

Louis A. Samstag, New York, N. Y.

Application December 16, 1936, Serial No. 66,556

Term of patent 3½ years

To all whom it may concern:

Be it known that I, Louis A. Samstag, a citizen of the United States, residing in New York, county and State of New York, have invented a new, original, and ornamental Design for a Vanity Case, of which the following is a specification, reference being had to the accompanying drawing, forming part thereof.

Figure 1 is a top plan view of a vanity case showing my new design;

Figure 2 is a view in elevation thereof;

Figure 3 is a bottom plan view thereof.

The dominating feature of the design com-

prises the combination with the top member of a body member, the outer wall of which extends laterally beyond the annular edge of the top member and is ornamented as shown, and the pearl-like device supported by the top member being bounded by an annular holding frame having a serrated inner ring and in contact with the pearl-like member, as shown.

I claim:

The ornamental design for a vanity case as shown and described.

LOUIS A. SAMSTAG.
